Westinghouse Electric & Manufacturing Com-
pany, East Pittsburgh, Pa., a corporation of
Pennsylvania

Application March 19, 1938, Serial No. 196,929

20 Claims. (Cl. 200—116)

The invention relates to control devices in general and more particularly to circuit breakers for controlling lighting and small motor circuits.

An object of the invention is the provision of a circuit breaker having an improved operating mechanism that is manually operable to open and to close the breaker contacts and automatically operable to effect opening of the contacts in response to predetermined overload conditions.

10 Another object of the invention is the provision of a circuit breaker embodying an improved operating mechanism for effecting quick make and break of the breaker contacts.

Another object of the invention is the provision 15 of a circuit breaker embodying an operating mechanism as previously described which when automatically operated effects movement of the operating handle to an intermediate indicating position.

20 Another object of the invention is the provision of a circuit breaker embodying an improved operating mechanism of the snap action type which is releasable for opening the contacts on overload and trip free of the manual operating handle.

25 Another object of the invention is the provision of a circuit breaker of the above type which has a small number of parts arranged so that the breaker occupies a minimum amount of space, and which is inexpensive to manufacture.

30 Another object of the invention is the provision of a circuit breaker embodying an improved operating mechanism having a small number of parts which are readily assembled and disassembled.

35 Another object of the invention is the provision of a circuit breaker embodying an improved thermally responsive trip means for effecting automatic operation of the breaker.

Another object of the invention is the provision 40 of a circuit breaker embodying an improved thermally responsive trip element which has a large controlling movement and yet which occupies a small amount of space.

Another object of the invention is the provision 45 of a circuit breaker embodying an improved bimetallic control element which has a large controlling movement and yet which has a small height.

Another object of the invention is the provision 50 of an improved thermally responsive control element which is pivotally mounted intermediate its ends to give a length of bimetal in two directions so that the flexing movement of each leg produces a relatively large deflection of the free end of the element.

The novel features that are considered characteristic of the invention are set forth in particular in the appended claims. The invention itself, however, both as to structure and operation together with additional objects and advantages thereof will be best understood from the following detailed description of one embodiment thereof when read in connection with the accompanying drawings in which:

Figure 1 is a vertical sectional view of a circuit breaker constructed in accordance with the invention, the breaker being shown in closed circuit position. 10

Fig. 2 is a vertical sectional view similar to Fig. 1 showing the breaker in the manually opened 15 position.

Fig. 3 is a sectional view similar to Fig. 1, showing the position of the parts following a tripping operation, and

Fig. 4 is a horizontal sectional view of the circuit breaker taken substantially on the line 20 IV—IV of Fig. 1.

Referring to the drawings, the reference numeral 1 designates an open sided casing of 25 molded insulating material in which the breaker contacts and operating mechanism are mounted. A cover 9 (Fig. 4) also of molded insulating material closes the open side of the casing 1 and is removably mounted thereon by means of a plurality of bolts 11. 30

A pair of end terminal strips 13 and 15 of 35 conducting material extend from within the casing 1 exteriorly thereof at each end. The strips 13 and 15 are removably mounted on the casing by being slid edgewise into suitable mounting recesses 17 provided therefor adjacent each end of the casing. The outer end of the strips 13 and 15 are perforated for receiving terminal screws 19 which engage threaded inserts 21 embedded in the ends of the casing 1. The terminal screws 19 serve to retain the strips 13 and 15 in mounted position after they have been slid into place in the casing 1, and also serve to electrically connect the breaker in an external circuit. 40

45 A stationary contact 23 is secured to the terminal strip 15 adjacent its inner end in a position to be engaged by a movable contact 25 which is actuated to open and to closed circuit position by the actuating mechanism of the breaker.

The operating mechanism of the circuit breaker comprises in general a pivotally mounted support or carrier 27, a contact arm 29 pivotally mounted on the support 27, an overcenter toggle

mechanism indicated generally at 31 for moving the contact arm to open and to closed circuit position and for biasing the pivoted support 27 to a tripped position, and a thermally responsive trip element indicated generally at 33 for releasably retaining the pivoted support 27 in an operative position.

The support 27 comprises two generally U-shaped plates 35 of sheet metal which are rigidly secured together in slightly spaced parallel relation by means of a plurality of rivets 37, the plates being spaced by suitable spacers (not shown). The support 27 is pivotally and removably mounted in the casing 7 by means of a fixed pivot stud 39 which is molded in and projects from the side wall 41 of the casing 7 and which extends through an opening provided therefor in one of the legs 43 of the support 27. The support 27 is spaced from the side wall 41 by means of a spacer sleeve 45 (Fig. 4) which surrounds the pivot stud 39. The opposite leg 47 of the U-shaped support 27 has a latch element 49 rigidly secured to the end thereof between the plates 35 by means of the rivets 37. The latch element 49 projects from the leg 47 of the support 27 and is adapted to be normally engaged by the free upper end of the thermally responsive trip element 33 to retain the support in operative position as shown in Fig. 1. The upper edges of the horizontal portions of the plates 35 of the support 27 form a limiting guide surface or track 51 for a roller of the overcenter toggle mechanism 31 as will hereinafter be described.

The contact arm 29 is pivotally mounted adjacent one end between the plates 35 of the support 27 by means of a pivot pin 53 which extends transversely between the horizontal portions of the plates 35 at a point substantially midway between the legs 43 and 47 of the support 27. The movable contact 25 is rigidly secured to the forward end of the arm 29 for movement into and out of engagement with the stationary contact 23. The upper edge of the contact arm 29 has a curved recess 55 formed therein above the pivot pin 53 to provide oppositely inclined curved surfaces 57 and 59 on opposite sides of the pivot axis 53 which are adapted to project above the limiting guide surface 51 of the support 27 for engagement by the roller of the overcenter toggle mechanism as it is moved back and forth along the guide surface 51.

The overcenter toggle mechanism for moving the contact arm 29 to open and to closed circuit position and for biasing the pivoted support 27 to a trip position comprises, in general, an operating handle 61, a link 63, a roller 65 and an overcenter spring 67. The operating handle 61 is of molded insulating material and is pivotally mounted intermediate its ends on a pivot stud 69 which is molded in the material of the casing and projects into a recess 71 provided in the top wall of the casing for accommodating the hub portion of the handle. The end edges of the recess 71 are beveled to provide stops for limiting rotation of the handle 61. The handle 61 has a knob portion 73 which projects outwardly of the casing and a depending forked portion 75 which carries a transverse pivot pin 77. The pivot pin 77 extends transversely across the longitudinal slot formed by the two legs of the portion 75 and is frictionally held in openings provided therefor in the legs of the forked portion 75 of the handle 61. The link 63 has its upper end slotted at 79

for slidably engaging the transverse pin 77 of the forked portion 75 of the handle 61. The lower end of the link 63 has a forked projection 81 which carries a transverse pivot pin 83 on which is journaled the roller 65. The overcenter spring 67, which is of the coiled compression type, encircles the link 63 and is constrained between the forked projection 81 carried at the lower end of the link and a washer 85 slidably mounted on the link 63 which is in turn engaged by the rounded lower end of the handle 61. The spring 67 thus serves to bias the roller 65 against the guide surface 51 of the pivoted carrier 27 so that the carrier 27 is always biased in a counter-clockwise direction about its pivot axis 39. The width of the forked projection 81 is only slightly less than the inner width of the casing so that the roller cannot be laterally displaced off of the guide track 51.

The thermally responsive trip element 33 comprises a strip 86 of bimetallic material having a high expansion side 87 and a low expansion side 89. The strip 86 is bent sharply intermediate its ends as indicated at 91 to provide a vertical leg 93 and a horizontal leg 95 which are substantially at right angles to each other. The strip 86 has a sleeve 97 rigidly secured thereto at the bend 91 to provide a pivotal mounting means for the strip. The strip has its sleeve pivotally mounted on a pivot stud 99 which is molded in and projects from the side wall 41 of the casing 7. An adjusting screw 101 engages the low expansion side 89 of the strip 86 adjacent the end of the horizontal leg 95 thereof, the screw 101 being mounted in a threaded insert 103 embedded in the base of the casing 7. The horizontal leg 95 of the strip 86 is biased in engagement with the adjusting screw 101 by means of a spring 105 carried by a stud 107 supported by the casing. The upper free end 109 of the vertical leg 93 of the strip normally engages the latch element 49 of the pivoted support 27 to restrain the support in operative position. One end of the bimetallic strip 86 is electrically connected to the movable contact 25 by means of a conductor 111, and the other end of the strip is electrically connected to the opposite end terminal 13 by means of a flexible conductor 113. The strip is thus electrically connected in series circuit with the contacts 23 and 25 of the breaker so as to be traversed by the current flowing through the circuit controlled by the breaker. The bimetallic element 86 being pivotally mounted intermediate its ends provides a length of bimetallic material in two directions from the pivot axis, so that the deflection of the free end 109 thereof is produced by the combined flexing action of the two legs 93 and 95. When the bimetallic element 86 is heated a predetermined amount by the passage of an overload current therethrough, the end of the horizontal leg 95 tends to deflect downwardly against the adjusting screw 101. This causes the bimetallic element to be partially rotated in a counter-clockwise direction to produce a deflection or movement of the free upper end 109 in a direction away from the operating mechanism of the breaker. Since the upper leg 93 is also heated by the current, the deflection of the upper free end 109 is increased by the flexing of the upper leg 93. It will thus be seen that the total deflecting movement is provided by the flexing of each of the two legs 93 and 95. The bimetallic element 86 being bent substantially in the shape of a right angle and pivoted intermediate its ends at the bend, in addition to giving a large deflect-

ing movement, also allows the element to be advantageously mounted between a corner of the casing 7 and a corner of the operating mechanism to provide a very compact structure and 5 to reduce the total space occupied by the breaker.

The trip characteristic or tripping point of the bimetallic trip element 86 is adjustable by means of the adjusting screw 101. Turning the adjusting screw in or out serves to change the amount 10 of overlap between the upper free end 109 of the trip element 86 and the latch element 49 carried by the pivoted support 27. Since the bimetallic trip element 86 has a relatively large deflecting movement, its trip characteristic may be adjusted 15 over a considerable range by means of the screw 101.

The pivotally mounted bimetallic trip element 86 is spaced from the side wall 41 of the casing 7 by means of a spacer sleeve 115 mounted on the 20 pivot stud 99 between the sleeve 97 and the side wall 41. A pair of spacer sleeves 119 mounted on the ends of the studs 39 and 99 serve to space the pivot support 27 and the bimetallic trip element 86 from the inner surface of the 25 cover 9 and these sleeves cooperate with the sleeves 45 and 115 to prevent lateral displacement of the support 27 and the trip element 86.

When two or more circuit breaker units as described above are required, the units may be assembled 30 together side by side, and in this case the side wall 41 of one unit serves to close the open side of the next adjacent unit and to retain the parts thereof in mounted position. Where several units are assembled together side by side, 35 a single cover 9 is used to close the open side of the end casing 7.

The assembly and disassembly of the circuit breaker unit is facilitated by reason of the fact that all of the main parts of the breaker are 40 movably mounted through the open side of the casing, the operating handle 61, the movable support 27 and the bimetallic trip element 86 being mounted by being slid onto their corresponding pivot studs which project from the side 45 wall of the casing 41, and the end terminals 13 and 15 being slid into the recesses provided therefor as previously described. The cover 9 serves to retain the assembled parts in mounted position.

50 Further features of the operating mechanism will be more fully understood in connection with the following description of the operation thereof. With the breaker in the closed circuit position as shown in Fig. 1, it will be noted that the actuating roller 65 engages the inclined surface 57 of the contact arm 29 which is disposed above the guide surface 51 of the pivoted support 27, and the line of action of the overcenter spring 67 and the roller 65 biased thereby is to the right of the pivot pin 53 which pivotally supports the contact arm 29. The contact arm is thus biased by the spring 67 and roller 64 to closed circuit position with a predetermined force to maintain the contacts 25 and 23 in pressure engagement. 55 Since the line of action of the overcenter spring 67 passes to the left of the pivot stud 39, the movable support 27 is biased by the spring 67 in a counter-clockwise direction but is retained in the operative position shown by means of the bimetallic trip element 86. In this position of 60 the parts, the line of action of the overcenter spring 67 and the roller 65 is substantially perpendicular to the tangent of the inclined curved surface 57 at the point of engagement of the 65 roller 65 therewith. To manually open the cir-

cuit breaker, the operating handle 61 is moved in a counter-clockwise direction from the position shown in Fig. 1 to the position shown in Fig. 2. This movement of the operating handle moves the pivot pin 77 carried by the lower end 7 of the handle to the right causing the roller 65 to roll down the inclined surface 57. As soon as the axis of the pivot pin 77 crosses the imaginary line joining the axis of the pivot stud 69 and the pivot pin 83, the roller 65 will be moved to the 10 left along the guide surface 51 with progressively increasing acceleration due to the expansion of the overcenter spring 67. During this movement of the actuating roller 65 to the left along the guide surface 51, it engages the opposite inclined surface 59 of the contact arm 29 and effects counter-clockwise rotation of the contact arm from the closed circuit position to the open circuit position as shown in Fig. 2.

In closing the circuit breaker substantially the reverse action takes place. The operating handle 61 is moved in a clockwise direction from the position shown in Fig. 2 to the position shown in Fig. 1. This clockwise movement of the operating handle 61 moves the pivot pin 77 to the left compressing the spring 67. As soon as the pivot pin 77 crosses the imaginary line, joining the pivot stud 69 and the pivot pin 83, the roller 65 is moved to the right along the guide surface 51 with progressively increasing acceleration due to the expansion of the spring 67. During this movement of the roller to the right along the guide surface, it engages and rides up upon the guide surface 51 of the contact arm 29 to effect clockwise rotation of the contact arm 29 to the closed circuit position shown in Fig. 1. The fact that the roller 65 engages the inclined surface 57 at a point above the guide surface 51 of the movable support 27 provides a definite pressure engagement between the movable contact 25 and the stationary contact 23 and also provides a certain amount of follow-up to compensate for burning or wearing away of the contacts. From the above description it will be seen that the contact arm 29 is moved by the overcenter toggle mechanism 31 to open and to closed circuit position with a snap action to secure quick make and break of the contacts irrespective of how slowly the operating handle 61 is moved by the operator.

50 In the event that an overload or short circuit condition occurs in the circuit in which the breaker is connected, the abnormal current flowing through the bimetallic trip element 86 heats the same causing the upper free end 109 thereof to be deflected to the left away from the support 27 to effect release of the pivoted support 27. When thus released, the support 27 is rotated in a counter-clockwise direction about its pivot axis 39 as a result of the biasing action of the overcenter spring 67. This movement of the support 27 causes the arm 29 to rock counter-clockwise on the contact 23 as a fulcrum to change the inclination of the surface 57. This causes the roller 65 to be moved to the left down 65 the inclined surface 57 of the contact arm and also down the now tilted guide surface 51, by the expansion of the overcenter spring 67. The movement of the roller 65 down the inclined surface 57 and also down the now tilted guide surface 51 is assisted and accelerated due to the fact that the line of action of the spring 67 changes as the roller moves down the inclined surface to aid movement of the roller. During this rolling movement, the roller engages the 70 75

opposite inclined surface 59 of the contact arm 29 to effect rotation of the contact arm to open circuit position as shown in Fig. 3. The counter-clockwise movement of the pivoted support 27 is limited by a pivot stud 123 which is molded in and projects from the side wall 41 of the casing 7. The movement of the actuating roller 65 from the position shown in Fig. 1 to the tripped position shown in Fig. 3 also causes movement 10 of the operating handle 61 in a counter-clockwise direction. This counter-clockwise movement of the operating handle is stopped by an inwardly projecting portion 125 of the leg 43 of the pivoted support 27, so that the operating handle assumes an intermediate indicating position as 15 shown in Fig. 3 to indicate the fact that the breaker has been tripped in response to an overload.

Before the breaker can be reclosed it is necessary to reset the support 27 to its operative latched position shown in Fig. 1. To reset the breaker following a tripping operation, the operating handle 61 is moved in a counter-clockwise direction from the position shown in Fig. 3 to 25 the open circuit position shown in Fig. 2. During this resetting movement of the operating handle, the legs of the lower forked end 15 of the handle 61 engage and move the inwardly projecting upper end 125 of the support 27 effecting 30 clockwise rotation of the support about its pivot axis 39 to return the latch element 49 carried by the support into latching engagement with the upper free end 109 of the bimetal trip element 86 which has been returned to its original position after being cooled. The breaker cannot be closed until after the mechanism is reset as described above. Thus if the operating handle is moved directly from the tripped position to the closed position without first resetting the mechanism, the line of action of the spring 67 will not be changed a sufficient amount to cause movement of the roller to the right up the tilted surface 51. After the breaker has been reset as previously described, the contacts may be reclosed by moving the operating handle 61 in a clockwise direction as previously described. It will be noted that the point of engagement of the latch element 49 with the upper free end 109 of the bimetallic trip element 86 is disposed in a vertical line substantially directly above the pivot stud 99 of the bimetallic trip element, so that the line of action of the force exerted by the support 27 on the bimetallic trip element 86 passes substantially through the pivot axis 99 of the bimetallic trip element. Thus the only force which must be overcome by the bimetallic trip element 86 as it deflects is that of the friction between the upper free end 109 thereof and the latch element 49.

The operating mechanism of the breaker is such that the movable contact 25 is entirely trip-free of the operating handle 61. That is to say, the tripping of the breaker in response to an overload will effect opening of the contacts even though the operating handle 61 is held in closed circuit position.

While the invention has been disclosed in accordance with the provisions of the patent statutes, it is to be understood that various changes in the structural details thereof may be made without departing from the spirit of the invention. It is desired, therefore, that the appended claims be given the broadest reasonable construction permissible in the light of the prior art.

I claim as my invention:

1. In a circuit breaker, a movable support member, means releasably retaining said support member in an operative position, a contact member pivotally mounted on said support member, one of said members having a guide surface, actuating mechanism including a means movable back and forth along said guide surface for moving said contact member to open and to closed circuit position. 5

2. In a circuit breaker, a movable support having a guide surface, means releasably retaining said support in an operative position, a contact arm pivoted on said support, means including a member movable back and forth along 15 said guide surface for moving said contact arm to open and to closed circuit position, an over-center spring for actuating said member and for biasing said support to a tripped position, said support when released causing movement of said 20 contact arm to open circuit position.

3. In a circuit breaker, a movable support having a guide surface, a bimetallic trip element normally releasably retaining said support in an operative position, a contact arm pivotally 25 mounted on said support, means including an actuating member movable back and forth along said guide surface for moving said contact arm to open and to closed circuit position, said trip element being operable in response to predetermined conditions to release said support. 30

4. In a circuit breaker, a movable support having a guide surface, means releasably retaining said support in an operative position, a contact arm pivotally mounted on said support, means 35 including an over-center toggle and a roller movable thereby back and forth along said guide surface for moving said contact arm to open and to closed circuit position.

5. In a circuit breaker, a movable support having a guide surface, means releasably retaining said support in an operative position, a contact arm pivotally mounted on said support, a toggle mechanism comprising a roller movable back and forth along said guide surface for moving said 40 contact arm to open and to closed circuit position, an operating handle movable to open and to closed position and an over-center spring movable by said handle for actuating said roller, said support when released being moved by said spring to a tripped position to cause movement of said contact arm to open circuit position. 45

6. In a circuit breaker, a movable support having a guide surface, means releasably retaining said support in an operative position, a contact arm pivotally mounted on said support, a toggle mechanism comprising a roller movable back and forth along said guide surface for moving said contact arm to open and to closed circuit position, an operating handle movable to open and to closed position and an over-center spring movable by said handle for actuating said roller, said support when released being moved by said spring to a tripped position to cause movement of said contact arm to open circuit position, and said handle to an intermediate indicating position.

7. In a circuit breaker, a movable support, means releasably retaining said support in an operative position, a contact arm pivotally mounted on said support, said arm having a guide surface, actuating mechanism including means movable thereby back and forth along said guide surface for moving said arm to open and to closed circuit position, said support when released caus- 70

ing movement of said contact arm to an open circuit position, and current responsive means operable to effect release of said support.

8. In a circuit breaker, a movable support, means releasably retaining said support in an operative position, a contact arm pivotally mounted on said support, actuating means including an actuating member movable in one direction for engaging a portion of said arm on one side of its pivot axis to rotate said arm to closed circuit position, and movable in an opposite direction for engaging another portion of said arm on the opposite side of its pivot axis to rotate said arm to open circuit position, said support being movable when released to cause said contact arm to move to open circuit position.

9. In a circuit breaker, a movable support, means releasably retaining said support in an operative position, a contact arm pivoted on said support, actuating means for moving said arm to open and to closed circuit position and for moving said support when released, said means comprising an actuating roller having rolling engagement with a portion of said arm, a movable operating handle and an over-center spring for actuating said roller to move said arm to open and to closed circuit position, said support when released causing said spring and roller to move said contact arm to open circuit position.

10. In a circuit breaker, a movable support, means releasably retaining said support in an operative position, a contact arm pivoted on said support, an over-center toggle mechanism including a spring biased roller movable back and forth along a portion of said arm for moving said arm to open and to closed circuit position, said support when released causing said mechanism to move said contact arm to open circuit position.

11. In a circuit breaker, a movable support, means releasably retaining said support in an operative position, a contact arm pivoted on said support and having a curved surface on one side of its pivot axis, actuating means for moving said contact arm to open and to closed circuit position and for moving said support when it is released to a tripped position to cause movement of said contact arm to open circuit position, said actuating means comprising an actuating roller movable back and forth along said curved surface to actuate said arm, a movable operating member and an over-center spring for actuating said roller.

12. In a circuit breaker, a pivoted support having a guide surface on one side of its pivot axis, means releasably retaining said support in operative position, a contact arm pivoted on said support and having portions on opposite sides of its pivot axis adapted to extend above said guide surface, an over-center toggle mechanism including a roller movable thereby back and forth along said guide surface for engaging said portions to rotate said arm to open and to closed circuit position, said support when released causing said mechanism to rotate said contact arm to open circuit position.

13. In a circuit breaker, a casing, relatively movable contacts in said casing, actuating means in said casing operable to open and to close said contacts, a thermally responsive trip element operable to cause opening of said contacts in response to predetermined conditions comprising a strip of bimetallic material having a high and a low expansion side and bent intermediate its ends to provide two legs at an angle to each

other, means pivotally mounting said strip at its bend on a fixed support in said casing adjacent one corner of said casing so that its legs are substantially parallel to the walls terminating in said corner, a stop engaging the low expansion side of said strip adjacent the end of one leg and means holding the end of said leg against said stop.

14. In a circuit breaker, a casing, relatively movable contacts in said casing, actuating mechanism in said casing operable to open and to close said contacts, trip means in said casing operable to cause said mechanism to open said contacts in response to predetermined conditions, said trip means comprising a strip of bimetallic material having a high and a low expansion side heated in response to the current flowing in the circuit, said strip being pivotally mounted intermediate its ends on a fixed support and disposed substantially parallel to and adjacent the inner surface of said casing, a stop engaging the low expansion side of said strip adjacent one end and means holding said end in engagement with said stop.

15. In a circuit breaker having relatively movable contacts and a spring biased member releasable to effect opening of said contacts, a thermally responsive trip means normally restraining said element and operable in response to predetermined conditions to release said member, said means comprising a strip of bimetallic material having a high and a low expansion side pivotally mounted intermediate its ends on a fixed support, one end of said strip normally engaging and restraining said member, a stop engaging the low expansion side of the strip adjacent its other end, the line of action of the force applied to said strip by said member passing substantially through the pivot axis of said strip.

16. In a circuit controlling device, relatively movable contacts, a thermally responsive control element operable in response to predetermined conditions to control said contacts, said element comprising a strip of bimetallic material having a high and a low expansion side, means pivotally mounting said strip intermediate its ends on a fixed support, a stop engaging the low expansion side of said strip adjacent one end and means holding said end in engagement with said stop.

17. In a circuit controlling device, relatively movable contacts, a thermally responsive control element operable in response to predetermined conditions to control said contacts, said element comprising a strip of bimetallic material having a high and a low expansion side, means pivotally mounting said strip intermediate its ends on a fixed support, an adjustable stop engaging the low expansion side of said strip adjacent one end for adjusting the control characteristic of said strip, and means biasing said end in engagement with said stop.

18. In a control device, a thermally responsive control element comprising a strip of bimetallic material having a high and a low expansion side, said strip being pivotally mounted intermediate its ends on a fixed support, and a stop engaging the low expansion side of said strip adjacent one end.

19. In a control device, a thermally responsive control element comprising a strip of bimetallic material having a high and a low expansion side, said strip being pivotally mounted intermediate its ends on a fixed support, and an adjustable means holding said strip adjacent one end.

20. In a circuit interrupter, relatively movable contacts, operating means for said contacts including a manually operable handle movable to open or to close said contacts manually, and thermal means operable upon overload of the circuit to cause automatic opening of said contacts, said

thermal means comprising a strip of bimetallic material pivoted intermediate its ends on a fixed support, and means holding said strip adjacent one end.

OLIVER S. JENNINGS. 5
